FRITZ BRÜCK, OF OSNABRÜCK, GERMANY.

AUTOMATIC SPEED-BRAKE FOR SUBMARINE MINES.

1,014,804.

Specification of Letters Patent. Patented Jan. 16, 1912.

Application filed December 8, 1909. Serial No. 532,104.

To all whom it may concern:

Be it known that I, FRITZ BRÜCK, engineer, subject of the King of Prussia, German Emperor, and residing at Osnabrück, Germany, have invented a new and useful Improvement in Automatic Speed-Brakes for Submarine Mines, of which the following is a description.

My invention relates to submarine mines of the class intended to be deposited or planted by torpedo boats and other boats adapted to such use. Mines of this character are used for obstructing harbors, navigable streams and other water areas in time 15 of threatened or actual war.

My invention relates particularly to such mines of this class as are provided with an anchor adapted to rest upon or attach to the sea bottom and provided also with means 20 enabling them (more exactly their heads) to ascend from-said anchor when the mine, as a whole, is cast into the water or planted until a predetermined depth below the surface of the water is attained, in which position 25 the mine proper is checked and fixedly held or clamped by a suitable device so that it can not ascend higher. Mines of this kind are commonly provided with a light cable, windable upon a drum attached to the mine, 30 terminating in a heavy weight or anchor. The head is so constructed as to be lighter than the volume of water which it displaces so that it will always tend to rise, from any depth to which it may have been submerged, 35 and float upon the surface of the water; by suitably determining the weight of this head the magnitude of the upwardly impelling force may be fixed as desired within wide limits.

40 In the operation of the mines as just described, the mine proper or head has a tendency, due to the hydrostatic pressure of the surrounding water, to dart up from the anchor with great velocity when cast overboard; and this velocity tends to be greater as the water into which the mine is deposited becomes deeper. When the predetermined point below the surface of the water at which the head is to be stopped is reached, 45 and the checking device is applied, the sudden strain thus put upon the apparatus is so great that there is grave risk of breaking the cord or the clamping device, or some other essential part of the mine, so as to either cast it loose or disable it altogether.

It is the object of my invention to pro-

vide means to eliminate this risk. This I accomplish by providing a brake to coöperate with the winding mechanism in such a way that the unwinding and, therefore, the upward movement of the head can not take place at a velocity exceeding a certain magnitude. The head, therefore, ascends to its position finally predetermined at a fairly uniform and low rate of speed, so that the 65 clamping device is able to act without undue strain being entailed either upon it, its related devices or the cable. I may, of course, and preferably do, provide the braking means with an adjustment by means of 70 which the speed of ascent permitted the head may be made greater or less at will. If the head is not stopped the moment it has attained the desired level but is allowed to overshoot, as it will if it rises at too great 75 velocity, it is clear that too great a length of cable will be unwound so that after the head and cable have been clamped said head will be nearer the surface of the water than is desired for the purpose intended.

80 Referring to the drawings, Figure 1 is a view showing an elevation, part section, of a mine of the class described as it would ordinarily appear when in position and attached to its anchor; Fig. 2 is a section considerably enlarged taken along line 2-2 of Fig. 1; Fig. 3 is a section, similarly enlarged, taken along line 3-3 of Fig. 2; Fig. 4 is a similar section taken along the line 4-4 of Fig. 3; Fig. 5 is a section taken along the 85 line 5-5 of Fig. 3; and Fig. 6 is an elevation corresponding to the sectional view shown in Fig. 4.

90 Referring to the drawings, *a* is a head containing explosives and embodying suitable arrangements for the detonation thereof, as is usual in the art. Suitably attached to *a* below is a drum *b*, adapted to have wound around it the light cable *c* terminating in an anchor *d*. Outside the drum and at one end 100 of the shaft thereof is a large spur gear *f* and attached to a main casing *g*, which surrounds the drum, is a clamping device *h* adapted to bind the cable *c* fast against said casing and prevent further separation of the 105 mine and anchor.

110 The braking device *i* comprises the housing *j* suitably attached to the drum casing. This housing is so shaped as to closely embrace two spur gears *k* and *l* meshing into one another and mounted upon spindles suitably journaled in the side walls of the hous-

ing. One of these spindles is prolonged outside of the housing and has fixed upon it, near its extremity, a pinion *m* meshing with the large gear *f*. One of the walls of the 5 housing *i* is double so as to form the chamber *n*, from which chamber orifices *o* and *p* open into the central chamber which contains the gears *k* and *l*. One of said orifices is upon one side of the longitudinal center 10 line of the housing and the other orifice symmetrically upon the other side of said line, while both orifices are upon the central line of the housing at right angles to the longitudinal line. The apparatus being assembled as shown, the housing is filled with a 15 suitable fluid medium, preferably some heavy non-acid oil.

Attached to and within a subsidiary casting at the bottom of the main casing and 20 through which runs the cable *c* and immediately adjacent said cable is a clamp *h*, operated by clock work (not shown) adapted to firmly grip the cable at the expiration of a predetermined time after the mine has 25 been cast into the water. The beginning of this time period may be fixed by the release of a suitable device attached to the mine just prior to the time said mine is cast overboard, or automatically, by some device 30 adapted to release when the mine strikes the water; other ways of fixing the beginning of this time period may be provided without departing from the spirit of my invention. Or, means dependent upon hydro- 35 static pressure and hence upon depth below the surface may be utilized to operate the clamp instead of timed mechanism.

The operation of the device is as follows: When the mine is first cast into the water, 40 the mine proper or head and anchor are compactly related and the cable *c* wound tightly upon the drum. As the arrangement sinks to the sea bottom the head, by reason of its buoyancy, tends to rise quickly 45 with reference to the descending anchor. The cable *c*, unwinding from and rotating the drum, since the drum rotates the spur gear *f*, tends to rotate the pinion *m* and, thereby, the two housed gears *k* and *l*. 50 Without the oil contained in the housing, these gears would spin around and offer no resistance other than the usual frictional resistance. Considering the contained oil, however, it is clear that said oil tends to be 55 compressed on one side of the longitudinal center line of the housing and that a contrary tendency exists upon the other side of said line. As the apparatus is constructed, the oil yields to this compression by passing 60 through *o* into the chamber *n* and thence into the inner chamber *q* through *p*. The rate at which the oil is permitted to pass through these orifices depends, of course, upon their size and this is determined, there- 65 fore, for the maximum speed which the mine

is to be permitted to have. To lessen this speed, I provide a screw *r* and a lock nut *s*; by setting *r* closer to or farther away from the orifice *p*, I obstruct the passage of the oil through said orifice and therefore, slow down the mechanism as a whole. 70

While in the above specification and in the drawings I have shown a special and preferred form of braking device as controlling the rate of ascent of the mine and while this form constitutes a part of my invention, I wish to make it clear that many other forms of braking device might be used to accomplish the same purpose and that the invention does not reside wholly in the specific structure employed. Thus, other forms of fluid braking mechanism might be used, as also housed fans operating to compress air, which may be given a certain rate of leak; or centrifugally acting devices might 80 be used. Any one of such brakes may be designated as a "speed brake." 85

Many other details might be altered without departing from the spirit of my invention, which I have embodied in the following claims. 90

I claim:

1. The combination, in a submarine mine of the class described, of a head, an anchor, a cable connecting said head and anchor, a winding drum for said cable, and a speed brake entirely independent of but driven by and controlling said winding drum. 95

2. In combination with the winding drum, in a submarine mine of the class described; a speed brake comprising a housing having two chambers, a pair of meshed spur gears embraced by one of said chambers, a spindle fixed to one of said gears and actuated by the winding drum, and a pair of orifices connecting the two chambers, said orifices being oppositely situated as to a line through the axes of the two spur gears, substantially as and for the purpose described. 100

3. In combination with the winding drum, in a submarine mine of the class described; a speed brake comprising a housing having two chambers, a pair of meshed spur gears embraced by one of said chambers, a spindle fixed to one gear and actuated by the winding drum, a pair of orifices connecting the two chambers, said orifices being oppositely situated as to a line through the axes of the spur gears, and an adjustable screw adjacent one of said orifices, substantially as and for the purpose described. 110

4. The combination, in a submarine mine of the class described, of a head, an anchor, a cable connecting said head and anchor, a winding drum, a speed brake entirely independent of but driven by and controlling said winding drum, and means for regulating the magnitude of the braking effect exerted by said speed brake. 125

5. The combination, in a submarine mine 130

of the class described, of a head, an anchor, a cable connecting said head and anchor, a winding drum and said cable attached to said head, and a speed brake entirely independent of but driven by and controlling said winding drum.

6. In combination with the winding drum, in a submarine mine of the class described; a speed brake comprising a housing having two chambers, a pair of connected gears actuated by the winding drum in one of said chambers and a pair of orifices connecting

the two chambers said orifices being located oppositely as to a line through the axes of the gears, substantially as and for the purpose described.

In testimony whereof I have hereunto affixed my signature in the presence of two subscribing witnesses.

FRITZ BRÜCK.
